UNITED STATES PATENT OFFICE.

SIDNEY C. HILLS, OF TORRINGTON, CONNECTICUT, ASSIGNOR TO THE TURNER & SEYMOUR MANUFACTURING COMPANY, OF TORRINGTON, CONNECTICUT, A CORPORATION OF CONNECTICUT.

CURTAIN FIXTURE.

Application filed April 28, 1921. Serial No. 465,173.

To all whom it may concern:

Be it known that I, SIDNEY C. HILLS, a citizen of the United States, residing at Torrington, county of Litchfield, State of Connecticut, have invented a certain new and useful Improvement in Curtain Fixtures, of which the following is a full, clear, and exact description.

My invention relates to curtain fixtures and has for its object to provide a simple and efficient fixture of the flat rod type in which inserts are employed in a new and efficient way for mounting the rods in sockets. It further has for its object to produce a new and improved socket for receiving a portion of such an insert.

The following is a description of an embodiment of my invention, reference being had to the accompanying drawings, in which:

Fig. 1 shows on a reduced scale a curtain fixture embodying my invention, the same being attached to the frame of a window;

Fig. 2 is an enlarged view of the same partly in section;

Fig. 3 is a side elevation of the same partly in section on the line 3—3, Fig. 2;

Fig. 4 shows an unformed blank from which the socket is made; and

Fig. 5 shows a section on the line 5—5, Fig. 2.

Referring more particularly to the drawings, 1 is the window frame. 2—2' and 3—3' are telescoping sections of rods of the flattened type, having their ends curved at 4—4. Each of these curved ends contains a wire 5, termed an insert, which is secured in place by the wrapping of the metal forming the telescoping sections around the same in the ordinary manner. These inserts have portions 6 at the ends of the sections 2—2' which are flattened so as to lie in planes at right angles to the axes of the adjacent portions of the curved sections, the flattened portions 6 being of a greater width than the diameter of the unflattened portions of the inserts. The legs of the inserts are provided on their inner sides with recesses 5'—5' into which the metal of the body portions 3 and 4 is forced so as to hold the inserts in place.

The socket plates 7 are bent so as to have a raised central portion 8, in the crown of which there are one or more vertical slots 9 whose ends terminate in enlarged portions

10, these enlarged portions being located 55 between the crown 8 and the base of the plate so as to be out of alignment with the metal constituting the crown 8 and in alignment with one another. The base of the socket comprises ears which are provided 60 with perforations for securing the socket in place.

The socket plate before it is bent is shown in Fig. 4, 9' being the narrower portion of the slot and 10'—10' being the enlarged 65 openings in which it terminates. When this blank is bent up so as to produce the crown 8, the flattened portion 6 can be passed through the openings corresponding to the portions 10'—10' so that the end of the 70 bracket is firmly supported thereby. In order to permit this the width of the slot 9 is made at least equal to the diameter of the round portions of the insert.

In order to limit the downward movement 75 of the portion 6, stops 11 are provided, the same being formed by turning outwardly the integral tangs shown in Fig. 4.

Preferably I make the inserts in U-form, as shown in Fig. 5, one leg of the U being 80 embraced by the upper portion of a section 2—2' and the other leg being embraced by the lower portion of such section.

As will be evident to those skilled in the art, my invention permits of various modifications without departing from the spirit thereof or the scope of the appended claims.

What I claim is:

1. In a curtain fixture, the combination of a vertically extending flattened rod, inserts in the ends of said rod, said inserts having vertical portions in line with the ends of said rod and flattened so as to lie in planes at right angles to the axes of said end portions, and socket members each having a vertical recess therein open at its upper end and adapted to receive and hold the flattened portion of one of said inserts.

2. In a curtain fixture, the combination of a vertically extending flattened rod having 100 its end portions curved about a vertical axis and arranged substantially at right angles to the remaining portion of the rod, inserts in the ends of said rod, said inserts having vertical portions in line with the ends of said rod and flattened so as to lie in planes at right angles to the axes of said end portions, and socket members each having a

vertical recess therein open at its upper end and adapted to receive and hold the flattened portion of one of said inserts, said inserts being U-shaped and said flattened portion being between the arms of said U.

3. In a curtain fixture, the combination of a vertically flattened rod, a U-shaped member having its ends secured to one end of the rod and having a vertical portion 10 provided with lateral projections, and a socket member comprising a base, a raised

portion arranged substantially parallel with the base having a vertical slot capable of receiving said member through the upper end thereof to hold said end of the rod in place by engagement of said lateral projections with the inner side of said raised portion, and a stop located below said slot for engagement with the lower end of said U-shaped member.

SIDNEY C. HILLS.
